UNITED STATES PATENT OFFICE.

JOHN K. BISHOP, OF LOS ANGELES, CALIFORNIA.

MOUNTING FOR ARTIFICIAL TEETH.

Application filed October 18, 1926. Serial No. 142,402.

My invention is a continuation in part of my application Serial No. 27,562, filed May 2, 1925, and it relates to mountings for artificial teeth as used in crown and bridge work, and 5 in other forms of dental restoration, and the purpose of my invention is the provision of a mounting which effects in a simple, efficacious, and inexpensive manner the securing and rigid locating of an artificial tooth in 10 proper position between adjacent teeth of a mouth and in such manner as to produce an artificial tooth of great strength, one capable of being replaced, and a tooth having a porcelain incisal cervical and occlusal portion.

I will describe only two forms of mountings for artificial teeth embodying my invention and will then point out the novel features thereof in claims.

20 In the accompanying drawings;

Figure 1 is a view showing in horizontal section one form of mounting embodying my invention in applied position;

Figure 2 is a sectional view taken on the 25 line 2—2 of Figure 1;

Figure 3 is a view similar to Figure 2, showing a modified form of mounting embodying my invention;

Figure 4 is a detail perspective view of the 30 head and dowel embodied in the mounting shown in the preceding views;

Figure 5 is a vertical sectional view taken on the line 5—5 of Figure 2;

Figure 6 is a view showing the artificial 35 tooth of Figure 2 in perspective.

Referring specifically to the drawings, in which similar reference characters refer to similar parts in each of the views, my invention in its present embodiment comprises a 40 head 15 shown in Figure 2 which is of a form corresponding to the lingual or palatal surfaces of the teeth to which it is applied with the upper and lower walls 15^a and 15^b converging from the outer side so that the head 45 is substantially trapezoidal shape in vertical section. This head may be formed of any suitable material such as metal or the like and is adapted to be soldered or otherwise secured to inlays 16 or other anchorages, the 50 latter being of conventional form and secured in sockets 17 formed in adjacent natural teeth 18.

Secured to the head 15 is a dowel 19 of 55 ovate form as when viewed in Figure 1, and of rhombic form as when viewed in Figure 2. It is constructed of a single strip of metal,

bent upon itself to provide portions 19^a oppositely curved longitudinally, while one of its ends is arranged in divergent relation and embedded in the head 15, as clearly shown in 60 Figure 1. The strip comprising the dowel is formed of resilient metal in order that the ovate portion of the dowel can be constricted or contracted to permit of its insertion into a pocket 20 of an artificial tooth 21. As clearly 65 shown in Figures 1 and 2, the artificial tooth 21 is formed at one side with a socket 22 corresponding in shape to that of the head 15 so as to snugly receive the latter. This socket 22 passes transversely across the lingual or 70 palatal surface of the tooth about the middle portion thereof, as shown in Figure 6, and conforms approximately to such surface. Extending inwardly from the socket 22 is the pocket 20. As shown in Figure 2, this pocket 75 extends downwardly and corresponds in shape to that of the dowel 19, thus presenting a restricted mouth 20^a through which the dowel is adapted to be forced when applying the tooth to the mouth.

In practice, the divergent ends of the dowel 19 are embedded and thus secured in the head 15 in casting the latter. The head in turn is soldered to the inlays 16; then the latter are applied to the natural teeth 18 so as to support the head in bridging relation to the teeth and in such manner that the dowel 19 extends outwardly and downwardly from the anterior side of the head. The pocket 20 of the artificial tooth 21 is now filled with cement or 85 other suitable plastic material and immediately applied to the dowel, with the latter injected through the restricted mouth of the pocket. As the dowel passes into the pocket, the restricted mouth thereof operates to force 90 the two portions of metal 19^a into contiguous relation, thereby constricting or contracting the ovate form of the dowel sufficiently to allow the complete insertion of the dowel into the pocket. With the pocket filled with cement, it will be understood that during this 95 operation the two portions 19^a are first contracted and then expanded to their normal spaced relation, thereby forcing the cement 100 from the outer sides of the portions to their inner sides so as to fill the void between the portions. In this manner a body of cement 105 is interposed between the portions to maintain the latter in fully expanded position and to preserve the ovate form of the dowel whereby the dowel is permanently retained within the pocket, thereby rigidly securing the artificial

105

110

tooth upon the head 15. During the insertion of the dowel into the pocket a partial vacuum is formed between the portions 19^a, and in order to insure the proper and complete filling 5 of the dowel with cement, the portions 19^a are formed with openings 19^b through which the semi-liquid cement can pass from the outer sides of the portions to the inner sides.

By virtue of the fact that the pocket 10 extends downwardly into the incisal or occlusal portion of the tooth, it will be clear that the dowel occupies a corresponding position. In this position the dowel serves to reinforce the incisal or occlusal portion of the tooth 15 so as to present a tooth of great strength to successfully withstand the great pressures to which it is subjected. Due to the inclined position of the dowel, any pressure exerted upwardly or downwardly on the tooth tends 20 to tighten the dowel within the pocket, and any stress exerted on the dowel is reinforced by the substantial head 15. The association of the head 15 with the artificial tooth also tends to reinforce the tooth and secure 25 the head in fixed relation to the tooth.

In applying the tooth to the dowel it is necessary to tilt the tooth and in this position the tooth is moved to pass the socket 22 across the pointed end of the dowel when 30 the dowel will readily locate the pockets. By reference to Figure 2, it will be seen that the cervical angle of the dowel is rounded as indicated at 20^b, and likewise the corresponding angle of the pocket is rounded. Because of 35 these rounded portions the dowel can be compressed in a longitudinal direction until its greatest width has entered the socket, when the pushing home of the dowel can be effected by an oblique movement of the tooth. This 40 permits the easy application of the tooth to the dowel and at the same time eliminates the danger of splitting the tooth.

Another important feature of my invention is that the dowel holds the cement in a continuous band of metal and even should the cement become granular and the metal lose its 45 rigidity, the cement could not be withdrawn from the pocket without breaking the dowel or porcelain, either of which would be almost 50 impossible. This allows the dowel to be made of semi-rigid metal or metal having a low degree of rigidity, thereby securing a high degree of tensile strength to effectively withstand longitudinal stresses. The outer surface 55 of the dowel is continually in contact with the inner surface of the pocket and hence does not eject any more cement than is occupied by the solid contents of the dowel, thus filling the entire interior of the dowel.

60 In Figure 3 I have shown my mounting applied to an artificial incisor tooth. In this adaptation it is possible to employ a cervical extension of porcelain as the case may require to secure the most sanitary and esthetic results. In the use of the dowel 20 is it not

necessary to depend on that portion of porcelain lying palatal or lingual to the edge of the dowel as it is held by that deeper portion of porcelain lying lingual to the greatest width of the dowel.

70 Although I have herein shown and described only two forms of mountings for artificial teeth embodying my invention, it is to be understood that various changes and modifications may be made therein without departing from the spirit of the invention and the spirit and scope of the appended claims. For example, the head 15 may be provided with two or more dowels 19 and the tooth 21 formed with two or more pockets 20 in which 75 the dowels are received and locked by cement in the manner previously described.

I claim:

1. A tooth having a socket extending across one side of the tooth and inclined in the direction of the incisal edge of the tooth, and a pocket extending from the bottom of the socket and also inclined in the direction of the incisal edge, a head fitted to the socket, and a dowel secured to the head and extending to the bottom of said pocket so that when the pocket is previously filled with cement the dowel will have interlocking engagement with the tooth when cement is set, the pocket being of rhombic form in a labio palatal direction and ovoid in a mesio distal direction, and the dowel of a corresponding form as the pocket to lie contiguous to the walls of the pocket.

2. A tooth as embodied in claim 1 wherein 100 the dowel is formed with openings in the walls thereof to facilitate the passage of cement into the dowel.

3. A tooth having a trapezoidal socket extending transversely of the lingual or palatal 105 surface of the tooth, a pocket extending from the bottom of the socket into the incisal or occlusal portion of the tooth and shaped to define a rhomb in longitudinal vertical section and an oval in longitudinal horizontal section, a head of a form corresponding to that of the socket and insertable transversely therein, and a dowel fixed to the head and of a form corresponding to that of the pocket, 110 said dowel being formed of resilient material 115 to permit contraction thereof and thus allow its insertion into the pocket, said pocket being adapted to contain cement so that when the dowel is inserted and the cement set a solid body will be formed in the dowel to lock the 120 latter against removal from the pocket.

4. A tooth as embodied in claim 3, wherein 125 the dowel is formed from a single length of material having its ends embedded in the head.

5. A tooth as embodied in claim 3, wherein the dowel is formed from a single length of material having its ends embedded in the head, and holes are formed in the material labial to the greatest width of the dowel.

6. A tooth having a socket therein, a pocket extending inwardly from the socket and of ovate form, a head in the socket, and a hollow dowel of ovate form in outline constructed of 5 resilient material to contract when inserting the dowel into the pocket and to expand after insertion to cause cement previously inserted into the pocket to fill the dowel and when set to lock the dowel within the pocket, the dowel 10 forming a continuous band around the cement to prevent removal of the latter from the pocket.
7. A tooth having a trapezoidal socket transverse its medial portion inclined in the 15 direction of its incisal edge in incisors and in the direction of the buccal cusp in molars and bicuspids, and a pocket extending in the same general direction from the labial or buccal wall of the socket and into the incisal portion of incisors and into the bucco-occlusal portion of molars and bicuspids, said pocket being 20 of rhomboidal form in a labio-palatal direction with the labio-cervical angle thereof rounded and ovoid in a mesio-distal direction, and a mounting having a head of a shape corresponding to that of the socket to fit within the latter and a dowel permanently fixed to 25 the head and extending into the pocket, said dowel in outline being of the same form as the pocket and constructed of resilient material and having holes therein whereby when the dowel is forced into the pocket where the latter previously has been filled with cement the dowel is first compressed and then expands forcing the cement inwardly through the holes filling the space within the dowel so that when set it maintains the dowel expanded 30 and thereby locks the dowel within the pocket.
8. A tooth having a trapezoidal socket 35

JOHN K. BISHOP.
